UNITED STATES PATENT OFFICE.

FLOYD W. NEWMAN, OF BRADFORD, PENNSYLVANIA.

FIREPROOF DOOR, SHUTTER, AND THE LIKE.

No. 872,534.

Specification of Letters Patent.

Patented Dec. 3, 1907.

Application filed February 7, 1907. Serial No. 356,177.

To all whom it may concern:

Be it known that I, FLOYD W. NEWMAN, a citizen of the United States, residing at Bradford, in the county of McKean and State of Pennsylvania, have invented new and useful Fireproof Doors, Shutters, and the Like, of which the following is a specification.

This invention relates to fireproof doors, window shutters, gates, etc., of the folding or collapsible type and its object is to provide a device of this character made up of telescoping sections having means whereby the device can be quickly collapsed or folded into a compact mass.

15. A still further object is to so construct the device as to render the same easy to operate.

With these and other objects in view the invention consists of certain novel features of construction and combinations of parts which 20 will be hereinafter more fully described and pointed out in the claims.

In the accompanying drawings is shown the preferred form of the invention embodied in a door.

25. In said drawings: Figure 1 is a section through the door the same being shown extended or closed; Fig. 2 is a similar view showing the door folded or collapsed; Fig. 3 is an enlarged horizontal section through a 30 portion of the door extended the connecting links, controlling rods and the ears to which said rods are pivoted being removed for the sake of clearness; Fig. 4 is a view partly in section and partly in elevation of a portion of 35 the upper part of the door and casing; Fig. 5 is a vertical transverse section through the lower portion of the door, the door section being shown with its walls each formed of a single thickness instead of hollow, as shown 40 in Fig. 3; Fig. 6 is a similar view through the upper portion of the door and its casing, the door sections in this view being also shown with walls of a single thickness. Fig. 7 is an 45 elevation of the lower portion of one of the door sections. Fig. 8 is a section through a portion of the door and through the slotted guide tube therein.

50. Referring to the figures by characters of reference, 1 is a door casing formed of sheet metal, one of the jambs 2 thereof constituting a housing for the door when the same is collapsed. The top 3 of the door frame also constitutes a housing for the upper ends of the door sections.

55. The door is made up of a plurality of sections each of which is preferably constructed

of sheet metal. Each wall of the section consists of a sheet of metal folded upon itself to form an outer portion 4 and an inner portion 5, one end of the outer portion being 60 bent inward as shown at 6 and riveted or otherwise secured to the adjoining portion of the inner portion 5. The two walls of the section are connected at their rear ends by a back plate 7 which extends throughout the 65 height of the section and is provided intermediate its ends with a shoulder 8 extending transversely of the section and provided at the center thereof with a slot 9.

The sections of the door are each closed at 70 the bottom as shown at 10 said bottom being curved upward from the front or open end of the door section to the rear or closed end thereof and is concavo-convex in cross section. A groove or channel 11 is struck 75 downward into the bottom of each door section and extends from front to rear thereof. This groove is of sufficient width to receive a roller 12 mounted on a shaft 13 which is secured beneath the highest portion 80 of the bottom of the adjoining door section.

The inner portions 5 of the walls of each door section have oppositely disposed slots 14 registering with slots 15 formed longitudinally within pipe sections 16 secured 85 within the walls of the door section. Asbestos or other suitable fire resisting material 17 is packed around the tubes 16 and entirely fills the space between the inner and outer portions of the walls of the door section. A rod 18 extends through the walls of each door section near the back plate 7 thereof and has laterally projecting ends on which are disposed guide rollers 19. The ends of each rod are adapted to project 95 through the slots 14 and 15 of the adjoining door section and the heads 19 are adapted to travel within pipe sections 16.

It is of course understood that the door sections are all of different widths so that 100 they can telescope as shown in Fig. 3 and the shoulders 8 are disposed at different distances from the bottom of the door as shown in Fig. 1 so that a connecting rod 20 which is pivoted within the housing 2 as at 21 can 105 extend through the slots 9. Depending from each shoulder 8 adjacent the slot 9 is an ear 22 to which the rod 20 is pivoted. Parallel links 23 are pivotally connected as at 24 to the outer faces of those door sections 110 adjoining the housing 2 and are pivoted at their lower ends as at 25 to the inner faces

of the adjoining door sections so that when the door is folded these links will assume positions between the sections. The remaining door sections are similarly connected 5 adjacent their lower ends by links 26. Ears 27 extend from the front of each door section at the sides thereof and on a line parallel with the rod 20 and pivoted to these ears and extending along the outer faces of 10 the door sections are controlling rods 28. The pivot 21 of rod 20 consists of a rod which extends through the walls of the housing 2 and is provided at its outer ends with actuating arms 29 having grips or handles 30. 15 The upper ends of the door sections are curved so as to be parallel or concentric with the bottoms of said sections and extending laterally from the upper portion of each door section are angle irons 31 adapted 20 to rest upon ledges 32 extending inward from the top of the door frame as shown in Fig. 6. It is of course understood that the outer door section has its front face closed as shown at 33. It is of course understood 25 that when the door is closed or extended the rods 18 assume positions in the front ends of slots 14 and 15 thereby preventing the sections from moving apart. Also the rollers 12 rest upon the floor as shown in Fig. 1 30 and the angle irons 31 contact with the ledges 32. When it is desired to open the door or fold it the operator swings the arms 29 upward. This will cause the strip 20, which is keyed or otherwise secured to rod 35 21, to also swing upward and as it is pivoted to each door section all of said sections will be simultaneously swung in an arc concentric with pivot 21. The rollers 12 will ride upward within the channels or grooves 11 40 and as the links 23 and 26 are parallel with the rod 20 the upper and lower ends of the sections of the door will be maintained in proper relation. When the rod 20 has been 45 swung into an upright position the sections of the door will be nested as shown in Fig. 2 and will be entirely disposed within the housing 2. In view of the fact that the door sections travel into each other upon the rollers 12 and the inclined bottoms 10 50 it will be obvious that the power required to collapse the door need only be sufficient to draw the sections upon the inclined bottom 10. When the door is closed it constitutes an efficient fireproof closure which 55 is not objectionable in appearance and which practically conceals the connections between the sections thereof.

It will be noted by referring to Figs. 5 and 6 that each of the door sections have 60 their side walls converging upwardly. As a result of this construction, the sections, when the door is collapsed, as shown in Fig. 2, will bind within each other. When, however, the sections are swung outward and 65 downward to close the door, the sections

will be moved out of binding position and will promptly drop to the position shown in Fig. 1.

What is claimed is:

1. A door comprising a plurality of parallel 70 telescopic door sections disposed to contact with and be supported by a floor, and means within and connected to each of said sections for compelling simultaneous movement thereof to extend or collapse the door. 75

2. A door comprising parallel telescopic door sections, means within and pivotally connected to the sections for preventing independent movement of said sections, each of said sections being disposed, when the 80 door is extended, to rest upon a floor, and when the door is collapsed to rest upon the adjoining door section.

3. A door comprising a plurality of telescopic sections, anti-friction means carried 85 by each section and movable upon the bottom of the adjoining section, and means for simultaneously shifting the sections to collapse or to extend the door.

4. A door comprising a plurality of telescopic sections having inclined bottoms, rollers carried by the sections and mounted to travel upon said bottoms, and means for simultaneously shifting the sections to collapse or extend the door. 90

5. A door comprising a plurality of telescopic sections, one end of each section being disposed to ride upon one end of the adjoining section, and means for simultaneously shifting the sections to collapse or extend the 100 door.

6. A door comprising a plurality of telescopic sections, parallel connecting devices pivoted to said sections, and means for simultaneously shifting the sections to collapse or 105 extend the door.

7. A door comprising telescopic sections, a housing, a rigid connection pivoted within the housing and extending through and pivoted to the sections, and means for swinging said connection to nest the sections within the housing. 110

8. A door comprising telescopic sections, a connecting strip concealed therein and pivoted thereto, pivotal connections between the sections for maintaining them parallel, and means for swinging the strip to nest the sections. 115

9. A door comprising telescopic sections having inclined bottoms, rollers carried by the sections and mounted to travel upon the bottoms of the adjoining sections, a strip within and concealed by the sections and pivoted thereto, and means for actuating said strip to nest the sections. 120

10. A door comprising telescopic sections having slotted shoulders intermediate their ends, a housing, a strip pivoted within the housing and extending through the slotted shoulders and pivoted to the sections, and 130

- means for swinging the strip to nest the sections within the housing.
11. The combination with a door frame constituting a housing, and a ledge carried by said frame; of a door comprising telescopic sections, outstanding portions thereon adapted to bear upon the ledge, and means within the sections for simultaneously raising the sections and nesting them within the housing, said sections being vertical. 5
12. The combination with a door frame constituting a housing, and a ledge carried by said frame; of a door comprising telescopic sections, outstanding portions thereon adapted to bear upon the ledge, means within the sections for simultaneously raising the sections and nesting them within the housing, and means for maintaining the sections at a fixed angle to the horizontal. 15
13. A door made up of a plurality of sections, each section consisting of opposite hollow sheet metal walls, packing within said walls, and a back plate connecting the walls. 20
14. A door made up of a plurality of sections, each section consisting of opposite hollow sheet metal walls, packing within said walls, a slotted and shouldered back plate connecting the walls, and a connection between the sections. 25
15. A section for collapsible doors consisting of opposite hollow sheet metal walls, packing within the walls, a back plate connecting the walls, and a slotted shoulder formed with the back plate. 30
16. A section for collapsible doors consisting of oppositely disposed hollow sheet metal walls having slots in their inner faces, slotted 35
- guides within the walls and registering with the first mentioned slots, a back plate connecting the walls, and projecting devices extending beyond the sides of the section. 40
17. A section for collapsible doors consisting of oppositely disposed hollow sheet metal walls having slots in their inner faces, slotted guides within the walls and registering with the first mentioned slots, a back plate connecting the walls, projecting devices extending beyond the sides of the section, and packing within the walls. 45 50
18. A door comprising telescopic tapered sections, a connecting device concealed therein and pivoted thereto, means for maintaining the sections parallel, and means for swinging the device to nest the sections. 55
19. A door comprising an actuating member, a connecting device movable with said member, and parallel telescopic door sections pivotally connected to and concealing said device and disposed to be extended or collapsed by the movement thereof, and means for maintaining the sections parallel. 60
20. The combination with a housing; of a plurality of telescopic door sections, means within and pivotally connected to the section for nesting said sections within the housing or extending them therefrom, and means for maintaining the sections constantly parallel with the housing. 65

In testimony that I claim the foregoing as my own, I have hereto affixed my signature in the presence of two witnesses.

FLOYD W. NEWMAN.
